UNITED STATES PATENT OFFICE.

HALLA F. GRAY, OF DENVER, COLORADO.

CARPET CLEANING PROCESS AND APPARATUS.

1,410,913.

Specification of Letters Patent. Patented Mar. 28, 1922.

Application filed June 9, 1919. Serial No. 302,690.

To all whom it may concern:

Be it known that I, HALLA F. GRAY, a citizen of the United States, residing at the city and county of Denver, and State of Colorado, have invented certain new and useful Improvements in Carpet-Cleaning Processes and Apparatus; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to a process and apparatus for cleaning carpets, rugs and like or similar articles. The invention may be termed a semi-dry process, as distinguished from wet washing on the one hand, and the ordinary pneumatic cleaning process on the other hand.

I have found that by applying to the carpet or rug to be cleaned, a dirt or refuse holding medium, such as vulcanized oil, either alone or mixed with powdered cork, sawdust or other similar material, and employing in connection therewith a small amount of liquid, as water or any of the so-called dry cleaning liquids, as benzine, gasolene, etc., I am able to thoroughly clean the carpet, the principle being that the soil or refuse holding medium has an affinity for the dirt and as soon as the dirt is loosened by the action of a brush or in any other suitable manner, it will cling to the holding medium and may be removed by suction in a manner similar to removing dust by using a pneumatic cleaner.

As soon as the dirt or soil is loosened from the fibers of the pile or nap of the carpet or other article, it clings to the holding medium, which prevents the dirt from sinking deeper into the pile or nap and makes it practicable to remove it with the medium by the action or power of the suction. The liquid and the medium cooperate to perform the dirt-loosening function under the action of the brush or other suitable device. The vulcanized oil is soft and moist in the crushed condition in which it is employed, and will of itself, without the aid of liquid, produce fairly good results, but better results, and practically perfect results, are obtained by employing the liquid in combination with the holding medium.

This holding medium may be used over and over again before its dirt-holding or carrying capacity has been exhausted, and I propose to employ a machine which combines the suction and blowing or blast operations whereby the suction acts to remove the dirt-carrying medium from the carpet, draws it into a fan chamber, and then expels it by a blast of air and returns it to the carpet through the medium of a suitable nozzle. When, however, the medium is sufficiently loaded with the refuse material, I discharge it into a refuse-holding receptacle, preferably of the bag form.

This process has advantages over both the wet washing and the strictly dry or pneumatic cleaning process, since it avoids the use of a relatively large quantity of liquid as is required in wet washing, and it produces results greatly superior to the strictly dry cleaning or pneumatic cleaning process where a carpet is badly soiled or contains dirt which clings to the pile or nap and therefore can not be removed by the pneumatic process, which only takes up the loose dirt and dust.

In the drawing I have illustrated a machine suitable for carrying out the process, and this will now be described.

In this drawing:

Fig. 1 is a central vertical longitudinal section of the machine, the plane of the section being indicated by the arrow 1 in Fig. 2.

Fig. 2 is a top plan view, partly in elevation and partly in section, on the line 2—2, Fig. 1.

Fig. 3 is a sectional detail, illustrating one construction for distributing the refuse-holding medium.

Fig. 4 is a side elevation of the machine with the bags removed, or shown in the condition for distributing the refuse-holding medium.

Fig. 5 is a sectional view of the fan chamber shown on a larger scale.

The same reference characters indicate the same parts in all the views.

Let the numeral 5 designate the framework of the structure considered in its entirety and comprising a nozzle, 6, a vacuum chamber 7, a fan chamber 8, a motor housing 9, and a gear case 10. The nozzle 6 is open at the bottom and its lower portion is in communication, as shown at 12, with the vacuum chamber 7, while the latter is in communica-

cation with the fan chamber by openings 13 and 14. The fan chamber is provided with openings 15 and 16, which are controlled by a slidable cut-off, 17, provided with an operating handle 18. The cut-off 17 is curved to conform to the curvature of the cylindrical chamber and is of sufficient area to close either of the openings 15 and 16, according as it may be necessary to cause a blast of air to pass through the opening 15 and through a conduit 19 to the nozzle, or pass through the opening 16 into a refuse receptacle, 20, which, as illustrated in the drawing, is in the form of a mesh bag adapted to retain the refuse material, but permitting the air to escape. One extremity of the receptacle 20 is connected with the handle 21 of the machine when the device is in use. The conduit 19 is flattened at its forward extremity, as shown at 22, and opens into the nozzle 6 and is utilized for the return of the refuse-holding medium when it is used over and over again, until its soil-holding capacity shall become exhausted, in which event the slidable cut-off, 17, is adjusted to close the passage 15 and open the passage 16 to allow the refuse-laden medium to pass into the receptacle 20.

As shown in the drawing, a suitable medium for holding the refuse material may be placed in each of two receptacles, 23, which are arranged above the opposite extremities of the nozzle, the bottom of each receptacle having perforations 24 which are controlled by a horizontally disposed slide 25, which is also provided with perforations 26. When the perforations 26 are brought into register with the perforations 24, the said medium passes from the receptacle to the carpet, and is distributed by the blast of air, and further, by rotary brushes 27 and 28, which are horizontally disposed and journalled in the opposite sides of a casing adjacent the vacuum chamber, as shown at 29. These brushes are preferably rotated in opposite directions, or in the directions indicated by the arrows in Fig. 1, through the medium of two belts 30 and 31, which connect pulleys mounted on a shaft 32, and other similar pulleys, 33 and 34, fast on the shafts of the brushes 27 and 28, respectively. Assuming that the pulleys on the shaft 32 are rotated in the direction indicated by the arrow in Fig. 4, the belt 31 should be crossed in order to cause the brush 28 to rotate in the proper direction or in the preferred direction.

The fan 35 within the fan chamber 8 is mounted on the shaft 36 of a motor 37. The motor shaft is also extended beyond the fan chamber, where it is provided with a worm, 67, which operates a worm wheel, 38, fast on the shaft 32. This worm gearing is enclosed within a housing or gear case, 39.

Mounted upon the framework of the structure, and as indicated in the drawing on top

of the motor housing 9, is a receptacle, 40, containing some suitable liquid, as water, benzine, gasoline, or, if desired, a soapy liquid. This liquid is delivered in suitable quantities to the forward extremity of the conduit 19, and to the opposite ends thereof, through the medium of suitable conduits, 41 and 42, which are in communication with the tank 40 at their rear extremities, and with the said conduit at their forward extremities, the forward end connections being designated by the numerals 43 and 44.

The receptacle 40 is provided with a valve, 45, for controlling the supply of liquid to the conduits 41 and 42. The stem of this valve 80 extends upwardly through the top of the receptacle 40 and its outer extremity 46 is exposed to enable the operator to manipulate the valve at will.

The machine is supported as it travels over the article to be cleaned, by wheels, 47, mounted on a shaft 48, which, as shown in the drawing, extends through the vacuum chamber in the rear of the brush 28. The machine is further supported by a rear wheel, 90 49, which is journalled in an arm 50, secured to the motor casing, as shown at 51.

In operating the machine, the latter is pushed over the carpet or rug 52 to be cleaned, the handle 21 being utilized for the purpose, this handle being forked as shown at 53, and its arms 54 being trunnioned at their forward extremities on the opposite sides of the motor casing. The current for operating the motor may be taken from an ordinary electric light circuit, by inserting a plug 55 in a suitable socket, the conductors 56 which are connected at one extremity with the plug being connected at their opposite extremities with the motor, as shown at 105 51a. This is an ordinary electric connection, as will be readily understood.

Assuming that the construction of the machine illustrated in Figs. 1 and 2 is employed, and that the refuse-holding or carrying medium is distributed simultaneously with the performance of the cleaning function, as the machine is moved over the carpet, the refuse-holding medium is sifted to the surface of the carpet and acted on by the brushes to thoroughly distribute it through the pile or nap of the carpet, thus bringing this medium in combination with a suitable amount of liquid taken from the tank 40, into intimate contact with the pile of the carpet, whereby the dirt is separated from the pile or nap. As this dirt has an affinity for the said medium, there is a union between them and the suction picks up the dirt-laden medium and carries it into the 115 fan chamber, after which the air blast drives the medium through the passage 15 of the fan chamber and thence through the conduit 19 to the nozzle, whereby this medium is used over and over until its capacity for 130

holding or carrying more dirt or refuse is exhausted. It will be understood that during such operation the passage 15 is opened to form free communication between the fan 5 chamber and the conduit 19, while the opposite passage 16 is closed. This is accomplished by the proper adjustment of the slidable cut-off, 17, as heretofore explained.

After the medium has been employed a 10 sufficient length of time, the cut-off is again adjusted to close the passage 15 and to open the passage 16, in which event the air blast drives the refuse-carrying medium into the refuse receptacle 20, where it remains until 15 removed.

If it should be preferred, the medium for catching and holding the dirt or refuse material to be taken from the carpet may be distributed over the surface of the carpet 20 before the carpet cleaning operation commences, in which event the operation of the machine may be absolutely the same since the medium would be taken up continuously from the carpet during the movement of 25 the machine thereover, and by the proper adjustment of the cut-off 17, the medium can be used until it has become completely saturated with the dirt. The distribution of the medium over the carpet, assuming that 30 it is done in advance of the performance of the cleaning operation, may be done either by hand or by the machine itself. If by the machine, the construction illustrated in Fig. 4 would be employed, the machine being 35 stripped of the conduit 19, the bag 20 and the liquid tank 40. As shown in the drawing, the tank 40 and the forward extremity of the conduit 19 are connected by the pipes 41 and 42, the forward extremity of 40 the conduit, as shown in the drawing, consisting of a metal member 57, to which the fabric of the conduit, is secured, this metal member having an opening communicating 45 with a nozzle 6 and being held in place by metal strips or bars 58, having flanges which overlap similar flanges formed on the lower edges of the part 57, the bars being connected with the nozzle by bolts 59 to whose upper extremities are applied wing nuts, 60. 50 By virtue of this construction, provision is made for readily removing the articles from the machine which are not needed during the operation of distributing the refuse-holding medium. Hence, the construction 55 shown in Fig. 4 is the same as that illustrated in Figs. 1 and 2 except that certain parts are removed, making the machine somewhat more easily operable.

It should be explained that as the dirt-holding medium is used over and over again, as heretofore explained, and worked through the pile of the carpet by the use of the brush or brushes, fresh surfaces of the medium are constantly exposed, to which 60 the dirt clings or adheres; and this opera-

tion is continued until the dirt-holding capacity of the medium is exhausted. It should also be explained that the action of the liquid, particularly upon the vulcanized oil, enhances the possibilities of the subdivisions of the medium, and therefore increases its dirt- and soil-holding capacity. 70

The refuse-holding medium constitutes a sort of body of material of low specific gravity, and therefore readily responds to 75 the action of the suction, which, alone or unaided, will not remove wet dirt from the pile or nap.

I claim:

1. The herein described process for cleaning carpets, rugs and the like, comprising continuously applying to the article to be cleaned a solid refuse holding medium to which refuse will adhere, subjecting the latter to such action as will cause the said 85 medium to be worked into and distributed through the fibers of the nap or pile of said article whereby the refuse is loosened and taken up by said medium, continuously removing and reapplying said medium in 90 cycles, applying moisture to said medium at one part of the cycle and finally removing the refuse laden medium.

2. A process of cleaning carpets, rugs and the like, comprising applying a refuse-holding medium to the article to be cleaned, subjecting the latter to such action as will cause the said medium to be brought into intimate contact with the fibers of the nap or pile of the said article, whereby the refuse is 100 loosened and taken up by the said medium, removing the medium by suction, returning it by an air blast to the article, repeating the circulation of the medium by the suction and blast until the medium is sufficiently laden with refuse, and finally discarding the refuse-laden medium. 105

3. The herein described process for cleaning carpets, rugs and the like, comprising applying a refuse-holding medium to the 110 article to be cleaned, applying moisture to the article, subjecting the latter to such action as will cause the medium and moisture to be brought into intimate relation with the fibers of the nap or pile of the article, whereby the dirt is loosened and clings to the said medium, removing the medium by suction, returning it by an air blast to the article and continuing the circulation of the medium by the suction and air blast 115 until the medium has become sufficiently laden with refuse, and finally discarding the refuse-laden medium by an air blast. 120

4. Apparatus for cleaning carpets, rugs and the like, comprising a forwardly located nozzle, a vacuum chamber in the rear of the nozzle and in communication therewith, a suction- and blast-generating means in communication with the vacuum chamber on the suction side and in communication with the 130

nozzle on the blast side, a refuse-holding receptacle also in communication with the blast side of the said means, and means for cutting off the blast in one direction and 5 causing it to act in the other direction, as may be desired.

5. Apparatus for cleaning carpets, rugs and the like, comprising a forwardly located nozzle, a vacuum chamber in the rear 10 of the nozzle and in communication therewith, means located in the vacuum chamber and arranged to act on the carpet to distribute and apply a solid refuse-holding medium to the article to be cleaned, suction- 15 and blast-generating means in communication with the vacuum chamber on the suction side and with the nozzle on the opposite side, the connections being unobstructed so as to permit passage of said 20 solid medium, whereby said solid medium may be returned to the article.

6. Apparatus for cleaning carpets, rugs and the like, comprising a forwardly located nozzle, a vacuum chamber in the rear 25 of the nozzle and in communication therewith, means located in the vacuum chamber and arranged to act on the carpet to distribute and apply a refuse-holding medium to the article to be cleaned, suction- and 30 blast-generating means in communication with the vacuum chamber on the suction side and with the nozzle on the opposite side, a refuse-holding receptacle also in communication with said means on the blast 35 side, and means for cutting off the blast in either direction and allowing it to act in the other direction.

7. Apparatus for cleaning carpets, rugs and the like having a nap, comprising a forwardly located nozzle, a vacuum chamber in the rear of the nozzle and in communication therewith, a suction- and air-blast-generating means in communication with the vacuum chamber on the suction side and in 45 communication with the nozzle on the blast side, said air-blast being adapted to apply through said nozzle a solid refuse-collecting medium to which refuse will adhere, and means to distribute and work said medium through and between the fibers of the nap, said suction being adapted to remove the 50 refuse-laden medium from the nap.

8. Apparatus for cleaning carpets, rugs and the like having a nap, comprising a forwardly located nozzle, a vacuum chamber in the rear of the nozzle and in communication therewith a suction- and air-blast-generating means in communication with the vacuum chamber on the suction side and in 60 communication with the nozzle on the blast side, said air-blast being adapted to apply through said nozzle a refuse-collecting medium to which refuse will adhere, means to distribute and work said medium through 65 and between the fibers of the nap, said suc-

tion being adapted to remove the refuse-laden medium from the nap, a refuse-receiving means having a connection leading to the blast side of said suction- and blast-generating means into which receiving means the blast is adapted to deliver the refuse-laden medium after removal from said nap and means for connecting the suction- and blast-means to and cutting it off from the nozzle and the receiving means as 70 desired.

9. Apparatus for cleaning carpets, rugs and the like having a nap, comprising a forwardly located nozzle, a vacuum chamber in the rear of the nozzle and in communication therewith, a suction- and air-blast-generating means in communication with the vacuum chamber on the suction side and in communication with the nozzle on the blast side, said air-blast being adapted 80 to apply through said nozzle a refuse-collecting medium to which refuse will adhere, means to distribute and work said medium through and between the fibers of the nap, said suction being adapted to remove the refuse-laden medium from the nap, a refuse-receiving means having a connection leading to the blast side of said suction- and blast-generating means into which receiving means the blast is adapted 85 to deliver the refuse-laden medium after removal from said nap, said receiving means being out of communication with the nozzle on the blast side and means for connecting the suction- and blast-means to and cutting it off from the nozzle and the receiving means as 90 desired.

10. Apparatus for cleaning carpets, rugs and the like having a nap, comprising a forwardly located nozzle, a vacuum chamber in the rear of the nozzle and in communication therewith, a suction- and air-blast-generating means in communication with the vacuum chamber on the suction side and in communication with the nozzle on the blast side, said air-blast being adapted to apply through said nozzle a refuse-collecting medium to which refuse will adhere, means to distribute and work said medium through and between the fibers of the nap, said suction being adapted to remove the refuse-laden medium from the nap, a refuse-receiving means having a connection leading to the blast side of said suction- and blast-generating means into which receiving means the blast is adapted to deliver the refuse-laden medium after removal from said nap, and a receptacle connected with the machine from which said medium may be fed to the nap of the article and means for connecting the suction- and blast-means to and cutting it off from the nozzle and the receiving means as 105 desired.

11. An apparatus for cleaning carpets, rugs and the like having a nap, comprising 110

ing a forwardly located nozzle, a vacuum chamber in the rear of the nozzle and in communication therewith, suction-producing means in communication with the vacuum chamber, a receptacle connected with the machine for supplying to the article a solid refuse-collecting medium to which refuse will adhere, and means to dis-

tribute and work said medium into and between the fibers of the nap, said suction-producing means being adapted to remove the refuse-laden medium from the nap, the connection passages being unobstructed so as to permit the passage of said solid medium. 10

In testimony whereof I affix my signature. 15
HALLA F. GRAY.
